UNITED STATES PATENT OFFICE.

SALLY C. REED, OF SAN FRANCISCO, CALIFORNIA.

GARMENT.

Application filed November 22, 1923. Serial No. 676,378.

This invention relates to women's undergarments of the type generally known as a "slip" as worn primarily in conjunction with other garments of sheer fabrics such as georgette, voile, and the like, and it has for its principal objects such a garment which is easily formed from a simple pattern, which will be more graceful, especially on the stouter figures, cling more toward the 10 limbs below the knees, provide a greater freedom to the movement of the hips and limbs, and to accommodate a sitting posture, also a garment which is easier to put on or take off than the present style of slip, 15 and one which has greater wear resisting features and incorporates the features of shadow panelling.

I attain the desirable features enumerated in the slip illustrated in the accompanying 20 drawings, and in which Figure 1 is a diagram showing the pattern to which the material is cut to form the skirt portion of my garment, and Figure 2 is a representation of a rear view of the completed 25 garment combined with a waist portion having the usual shoulder straps common to such articles of women's wearing apparel.

Before describing the specific forming of my improved slip it would be well to call 30 attention to the fact that heretofore such slips have been a simple tubular article to slip over the underclothing, and in some instances pleated to provide greater freedom; whereas, the essential features of my 35 slip are a tubular skirt portion folded to form an overlapping double rear wall with both vertical edges of the material free, and the overlapping walls being given a certain "lift" at the juncture of the skirt with the 40 waist portion, thereby in a very simple manner reducing the width of the skirt portion at the bottom.

In Figure 2 the waist portion is designated (1) and is a tubular body embracing 45 no unusual features. It is supported to the wearer by the shoulder straps (2). The skirt portion (3) is sewed to the waist portion at (4) and the overlapping rear walls are designated (5) and (6) and the front 50 wall (7).

The free vertical edges of the flaps are respectively indicated at (8) and (9) and on account of the "lift" given the upper corners (8') and (9') of the two ends of the material (8) and (9) as described, it resulted in narrowing the lower width of the garment as shown by the dimension line (10) as against the normal width (11) over the hips.

Above the hips the garment is preferably contracted by a dart at each side in the usual manner. To hold the free lower corners of the flaps in place they are preferably weighted in the corners as indicated at (12) and along the lower edge is the usual 60 hem (13). The pattern, Figure 1 shows the manner of cutting the material for the skirt from a rectangular piece of goods (14), and the extreme ends of the material are shown cut at an angle as at (15) to form the 65 vertical free edges (8) and (9) of the completed dress when folded to position as indicated by the encircled numerals.

The upper edge shows the hip darts at (16—16) and the goods tapered off below 70 the original blank (14) to provide for the "lift" of the corners (8') and (9').

Having thus described my improved slip, it will be seen that it provides a garment of unusual grace while embodying the structural advantages as pointed out in the general statement, and it is apparent without illustrated that some of its features would be valuable apart from combination with the waist portion.

I claim:

A skirt of the character described comprising a tubular body formed of material with the ends circumferentially overlapping to form a double back panel and of reduced diameter at the bottom edge and with free vertical edges at opposite sides of a wearer, the lower edge of the respective overlapping ends slanting downward from the lower corner and a weight secured 90 to each lower corner.
